UNITED STATES PATENT OFFICE.

JOHN THOMAS WAY, OF WELBECK STREET, COUNTY OF MIDDLESEX,
ENGLAND.

IMPROVEMENT IN ELECTRIC LIGHTS

Specification forming part of Letters Patent No. 33,457, dated October 8, 1861.

To all whom it may concern:

Be it known that I, JOHN THOMAS WAY, of Welbeck Street, in the county of Middlesex, in the United Kingdom of Great Britain and Ireland, have invented certain new and useful Improvements in Obtaining Light by Electricity; and I do hereby declare that the following is a full, clear, and exact description of the same, reference being had to the accompanying drawing, forming part of this specification, said drawing representing a vertical section of an electric lamp.

Heretofore in obtaining light by electricity electrodes of charcoal have usually been employed, and motion has been given to such electrodes by means of clock-work or magnets, or both combined, so as to change their acting points as they are consumed; but even with the best means yet employed for this purpose it is difficult, if not impossible, to obtain a constant light, and this defect is especially objectionable in the case of light-houses and in other circumstances where lenses are used, as the path of the rays of light is continually changing, and the distance to which they penetrate will greatly vary from time to time. The mechanical arrangements of electric lamps with charcoal electrodes are also of a delicate and complicated character, and very liable to get out of order, and cannot be readily repaired by workmen of ordinary intelligence.

The object of my invention is to obviate the above-mentioned difficulties and objections, and to this end it consists, first, in the use for one of the electrodes of a stream of mercury or other suitable conducting material capable of flowing, in combination with apparatus for regulating the distance apart of the two electrodes, such material being caused to flow through an orifice upon the surface of the conducting material which constitutes the second electrode, and the said orifice and the second electrode being so adjusted relatively to each other that the surface of the second electrode is situated at a point where the separation of the particles of the stream commences, as hereinafter described.

The invention consists, secondly, in the use for the second electrode, in combination with the flowing electrode, of a small overflowing cup or regulated surface of mercury or other suitable material similar to that of which the

flowing electrode is composed, the said material being received from the flowing electrode within the said cup or upon the said surface, and falling therefrom into a suitable receptacle, from whence it may be returned to the receiver or cistern from which the flowing electrode is supplied.

To enable others to apply my invention to use, I will proceed to describe the lamp represented in the drawing, and then refer briefly to some modifications of which the invention is capable.

A is a cistern, of iron, glass, slate, or other suitable material, from which mercury is conveyed by a pipe, *a b*, fitted with a stop-cock, *d*, to a jet, *c*, made of infusible clay or other material capable of bearing great heat, and having as small an orifice as can be conveniently made, from which the mercury will flow in a constant stream, which constitutes the flowing electrode.

The necessary pressure is obtained by placing the cistern at some distance above the orifice of the jet from which the mercury issues. I prefer a height of from six to twenty-four inches; but this height will depend upon the size of the conducting-tube, the size of the orifice of the jet, the strength of the electric current, and other circumstances. I therefore arrange the cistern in such a manner upon its support *B* that its height above the jet may be increased or diminished at pleasure, and to permit this the portion *a* of the pipe *a b* is made of india-rubber or other flexible material. The necessary pressure might be obtained by mechanical means.

The portion *b* of the pipe is made of iron, and in the example of my invention represented in the drawing is made of goose-neck form to give the jet a downward direction, the electrodes being inclosed within a glass bell-shade, *C*, supported on and secured air-tight to an iron plate, *D*, through which the pipe *b* passes, and in which it is secured. I propose, however, in some cases to use, in place of the bell-shade, an upright glass cylinder, fitted at top and bottom with plates of iron cemented to it air-tight, and to have the mercury-pipe enter the said cylinder through the top plate. I also propose to use as a substitute for glass a lantern-like frame having sheets of mica fitted in an air-tight manner.

The drawing represents the employment, as the second electrode, of a small overflowing cup, E, of mercury. This cup, arranged directly under the jet c, is made of clay, supported on a tube, G, of iron, which is fitted to work up and down through the plate D, under the control of a toothed rack, e, on the said tube, and a pinion, f, on a shaft, g, arranged in bearings attached to the bottom of the plate D, said rack and pinion constituting the means of adjusting the distance between the electrodes.

The cup E may be made of any diameter and depth; but the size I prefer is of about from half an inch to three-quarters of an inch in diameter, and one-quarter of an inch to three-eighths of an inch in depth. This cup is made with a long stem, h, of clay, which is cemented into the tube G, and which also serves to insulate from the plate D both the mercury in the cup and the conducting-wire i, which forms the communication between the said mercury and one pole (preferably the negative pole) of the battery, the wire forming the positive pole being in connection with the mercury flowing to the jet c.

When the glass cylinder with iron top and bottom plates is used instead of the bell-glass the jet-tube entering the cylinder through the top plate is insulated from the mercury in the cup E by the glass cylinder itself, and insulation of the said mercury from the bottom plate, D, becomes unnecessary, and hence in that case the mercury-cup E may be made of iron.

The plate D is fitted with a pipe, H, for the escape to a suitable receptacle below of the mercury which overflows from the cup E onto the said plate.

The chamber formed within the bell-glass C, or glass cylinder, must be perfectly tight against the escape of mercurial vapor.

The mercury collected from the pipe H may be returned to the cistern A by means of pumps, revolving buckets, or other devices, and the power of the battery may, by the use of well-known electro-magnetic machines, be employed for this purpose.

It is not absolutely necessary to the success of my invention, though I prefer that the overflowing cup or surface of mercury be used as the second electrode, as a pencil of charcoal may be employed, said pencil being held by a rod or tube working through a suitable opening in the plate D, and the said rod or tube having applied to it a traveling screw, a rack and pinion, a spring, or any other device for feeding the said pencil toward the jet c as fast as it is consumed, such device being adjustable by hand, or operating automatically.

Having explained the nature of my invention and the apparatus by which it is carried into practice, I will now explain the principle upon which the flowing electrode operates.

It is well known that when a current of electricity is made to pass through a conductor, such as a thin wire of metal, which is insufficient in conducting power to allow of the ready passage of the electricity, heat is generated; and if the current be powerful the conductor becomes red or white hot. The small stream of mercury issuing from the jet c has the character of a fine wire. Now, it will be found on examination that at a distance from the orifice of the jet dependent upon the force with which the stream is made to issue and the size of the stream, the dark metallic appearance of the mercury changes to a silvery hue, owing to a partial separation of the particles from each other. At about this point the greatest resistance to the passage of the electricity occurs, and at this point the light will be obtained.

I have spoken of the use of other substances than mercury for the flowing electrode. I have contemplated the use of powdered charcoal, the filings of iron or other metal, and of fusible metal kept liquid by heat; but in the use of fusible metal, in order to avoid the rapid oxidation of the metal, the case in which the light is exhibited should be kept full of carbonic acid or other suitable gas, to exclude the air, and for these reasons and others I consider it better to use mercury.

Other metals, as strontium or bismuth, may be mixed with the mercury to give different colors to the light obtained.

I do not claim, broadly, the employment of a stream of mercury as an electrode in apparatus for obtaining light by electricity; neither do I claim the adjusting of an electrode by mechanical means, when separately considered; but,

What I claim as my invention, and desire to secure by Letters Patent, is—

1. The use of a flowing electrode of mercury or other suitable conducting material, in combination with apparatus for regulating the distance apart of the two electrodes, substantially as herein described.

2. The combination of an overflowing cup or regulated surface of mercury as a second electrode with a flowing electrode of mercury in apparatus for obtaining light by electricity, substantially as and for the purpose herein set forth.

J. THOMAS WAY.
